UNITED STATES PATENT OFFICE.

EDWARD A. CHRISTOPH, OF CHICAGO, ILLINOIS.

LOCK.

1,384,179.

Specification of Letters Patent. Patented July 12, 1921.

Application filed August 25, 1919. Serial No. 319,579.

To all whom it may concern:

Be it known that I, EDWARD A. CHRISTOPH, a citizen of the United States, residing at Chicago, in the county of Cook and 5 State of Illinois, have invented a certain new and useful Improvement in Locks, of which the following is a full, clear, concise, and exact description, reference being had to the accompanying drawings, forming a 10 part of this specification.

My invention relates to locks, and is concerned particularly with locks of the so called "block-tumbler" type.

Locks of this general description comprise a stationary element and a rotatable element. The rotatable element is connected with the locking bolt mechanism of a door, or the like, in such manner that the locking bolt is released or thrown upon rotation thereof. The rotatable element is barred against rotation until the proper key is inserted whereupon this element is free to rotate and the locking bolt is released. The essential requisites in a lock of this type are, 15 a high order of security and a vast capacity for key changes or combinations, whereby the rotatable element is released for rotation. The provision of a lock possessing both has been a considerable practical difficulty here- 20 tofore in the art.

For example, in locks of this type as heretofore constructed it has been customary to employ a relatively great number of very thin block tumblers to facilitate various key 25 changes. Such construction does not possess the security that is derived from solidity and strength to resist violence. Furthermore a great number of thin tumblers are not only difficult to assemble accurately, but hinder 30 easy entrance of the key into the lock. To increase the thickness of such tumblers, as heretofore constructed would necessitate correspondingly increasing the length of the coöperating bittings in the key which is impractical; a great number of such tumblers making for an impractical lock and a cumbersome key whereby the key changes are 35 restricted.

The objects of my invention are:

50 (a) The provision of a lock capable of an infinite number of key changes or combinations.

(b) The provision of a lock possessing security derived from solidity and strength to resist violence. 55

(c) The provision of a lock possessing security against illicit opening, whether by picking or the use of a key surreptitiously obtained.

(d) The provision of a lock of the simplest construction, consistent with strength and durability; capable of resisting violence and hard usage without derangement. 60

(e) The provision of a lock wherein the key will enter easily and operate the lock 65 quickly.

Other aims of my invention not hereinbefore set forth will appear from the following detailed description and the claims taken with an inspection of the accompanying drawings wherein: 70

Figure 1 is a longitudinal, vertical, sectional view of a lock embodying my invention.

Fig. 2 is a cross sectional view taken on 75 the line 2—2 of Fig. 1.

Fig. 3 is a cross sectional view taken on the line 3—3 of Fig. 1.

Fig. 4 is a longitudinal, horizontal section taken on the line 4—4 of Fig. 1. 80

Fig. 5 is a perspective view of the rotatable tumbler carrying plug member of the lock.

Fig. 6 is a perspective view of the head or cap provided in connection with the plug 85 member shown in Fig. 5.

Fig. 7 is a front elevational view of a flat spring employed in connection with the lock mechanism.

Fig. 8 is a longitudinal, vertical, sectional 90 view of a modification.

Fig. 9 is a front elevational view of the same.

Fig. 10 is a longitudinal, horizontal section taken on the line 10—10 of Fig. 8. 95

Fig. 11 is a cross sectional view taken on the line 11—11 of Fig. 9, and Fig. 12 is a vertical sectional view through the spring sockets of two adjacent tumblers.

Referring to the drawings the rotatable 100 element of my improved lock is in the nature of a tumbler bearing plug member 1, revolvably mounted in a stationary inclosing element 2, which stationary inclosing ele-

ment bears a fixed relationship to the surface of the door. While in this particular instance the stationary inclosing element 2 is in the form of a casing or barrel the same 5 can, under certain conditions, be made an integral part of the door. At any event the inclosing element 2 is provided with a plug receiving bore 3 and a pair of diametrically opposite longitudinal grooves 4 and 5, with 10 which the tumblers 6, 7, 8, and 9 are adapted to coöperate to lock the plug member 1 against rotation.

The forward end of the plug receiving bore 3 terminates in a suitable co-axial 15 pocket 10. The inner or rear end of the tumbler bearing plug member 1 is connected with the bolt mechanism of the door in such manner that the same is released upon rotation of the plug member. This connection 20 might be through a suitable eccentric pin 11, projecting inwardly from the rear end of the plug member 1 and thence through a suitable cam or bolt thrower or otherwise; such connections being immaterial in so far 25 as my invention is concerned.

The rotatable element or tumbler bearing plug member 1 is bifurcated or slotted diametrically as shown at 12 in Fig. 4; thereby providing a pair of spaced partially annular prongs 14 and 15, between which the block tumblers 6, 7, 8 and 9 are accommodated transversely with respect to the axis of the plug. A diametrical groove 16 is provided in the plug member 1 between the 30 rear end of the slot 12 and the inner or rear end of the plug member. An inner or rear key-way guide block 18 is securely driven into this diametrical groove 16 and is provided with a key-way or slot 19 which serves 35 to guide and retain the inner end of the key, which is illustrated at 20 in Fig. 1, in position. The groove 16 might be in the form of a dovetail groove, if so desired. The eccentric pin 11 through which the plug 40 1 is connected with the locking bolt mechanism of the door is either formed integral with the rear end of the plug or is otherwise suitably attached thereto, so as to project rearwardly therefrom. The forward 45 face of this rear end of the plug 1 is counter-bored or countersunk as shown at 21, (Figs. 1 and 4) to allow sufficient clearance for the inner end of the key 20.

The forward end of the key 20 is guided 50 and retained in position by means of suitable outer key-way guide blocks 22, 23, and 24 provided with suitable registering slots or keyways 25. Alined ridges 26 project into the slots or keyways of the blocks 18, 22, 23, 55 and 24 and are adapted for coöperation with a groove 27, extending lengthwise of the key 20. The slots or keyways 19 and 25 can be supplemented at either side by suitable grooves for coöperation with a ridge 60

extending lengthwise of the key; the groove 65 27 can be provided in the opposite side of the key or arranged at various transverse positions to multiply the number of key changes as well understood by those skilled in the art. The upper and lower inner edges 70 of the innermost block 22 of the outer key-way guide blocks are milled or otherwise machined down, as shown at 28 in Fig. 1.

The plug member 1 is provided with a cup shaped head or cap 30 into which the outer 75 free ends of the partially annular prongs 14 and 15 are sprung. The outer keyway guide blocks 22, 23, and 24 are then forced into place between the outer ends of the prongs 14 and 15 and into coöperation with 80 the front wall of the head or cap 30. Indentations 32, (Fig. 5) are milled or otherwise provided in the partially annular peripheries of the prongs 14 and 15 adjacent the free ends thereof. The plug member 1 85 with the head or cap 30 in place is then inserted in a press and the annular edge 33 of the head 30 is operated upon, swaging the edge of the head into the indentations 32 and into the upper and lower milled out 90 portions 28 of the keyway guide block 22. The head 30 is thereby effectively riveted to the bifurcated or slotted tumbler carrying plug 1, and the blocks 22, 23 and 24 are effectively secured in place. 95

While I have shown four tumblers in this particular instance, this is merely illustrative and is immaterial, as any desired number of tumblers can be employed. Each of the tumblers 6, 7, 8, and 9 is provided with 100 a slot or keyway 40, arranged in this instance at successively different heights, (Fig. 1) in the tumblers 6, 7, 8 and 9 respectively. The upper and lower edges of the slots or keyways 40 are inclined as shown at 41 to the 105 axis of rotation of the plug member 1, thereby positioning the key engaging edges 42, adjacent the inner faces of the tumblers. Thus, the key engaging edges 42 of the tumblers are not disposed intermediate the opposite faces of the tumblers, but are disposed offcenter, or as shown, adjacent the rear faces of the tumblers. 110

This offcenter disposition of the key-engaging edges 42 is a highly important aspect of my invention in that I am thus 115 enabled by employing only two different tumblers to provide a practically infinite or unlimited number of key changes. The tumblers 6 and 9 are alike as are the tumblers 7 and 8; that is, the positioning of the slots or keyways 40 in these tumblers is identical, the tumblers themselves being simply reversed end for end in the plug member 1. 120

Between each of the block tumblers 6, 7, 8, and 9 a helical spring 45 is disposed in suitable coöoperating semi-circular pockets 125

46 and 47, provided in the opposite faces respectively of each of the tumblers. The semi-circular pocket 46 is milled from the upper edge of the tumbler 9, while the semi-circular pocket 47 is milled from the lower edge of the tumbler 8 as clearly shown in Figs. 2 and 3. When the tumblers 8 and 9 are placed together a complete circular pocket is provided, (Fig. 4) confining the 10 helical spring 45.

Normally the successive tumblers are separated vertically by the tension of the springs 45 bearing at their opposite ends against the lower ends 48 of the grooves 46, 15 and at the upper ends 49 of the grooves 47 respectively. Upon such separation the upper and lower edges of the tumblers are projected from the periphery of the plug member 1 as shown in Figs. 2 and 3 and into 20 coöperation with the longitudinal grooves 4 and 5 respectively, provided in the inclosing element 2 of the lock. In this condition the plug member 1 is barred against rotation and it is consequently impossible to release 25 the bolt mechanism of the lock. The tension of the springs 45 need not be great, and there is no appreciable resistance upon the insertion of the proper key and in holding the key fully inserted during the turning.

30 When the proper key 20 is inserted its tapered end or nose 55 passes through the keyways or slots 25 provided in the guide blocks 22, 23, and 24, through the keyways 40 provided in the tumblers 9, 8, 7 and 6 respectively through the inner or rear guide block 18 and into the recesses 21, provided in the forward face of the inner end of the plug 1. The shoulder 37 which separates the finger piece 35 and body portion 36 of 40 the key, coöperates with a diametrical groove 38 provided across the outer face of the head or cap 30 of the plug 1. The inclined shoulders 56 which are offset substantially the width of a tumbler along the upper and 45 lower edges of the body portion 36 of the key 20, coöperate successively with the inclined edges 41 of the keyways 40, raising and lowering the respective tumblers until the offcenter key engaging edges 42 thereof 50 are properly positioned upon the ledges 57 running lengthwise of the key between the inclined shoulders 56 thereof. The insertion of the correct key thus withdraws the tumblers from their projected positions 55 shown in Figs. 2 and 3 into the plug member 1, until the upper and lower edges of the tumblers either coincide with or lie within the periphery of the plug member. The plug member is now free to rotate 60 within the cylinder, the tumblers 6, 7, 8 and 9 traveling with the plug upon such rotation. If any but the correct key is inserted, however, the tumblers will not be raised or lowered as the case may be to the

proper point and the plug 1 will still be 65 barred against rotation.

Since the key engaging edges 42 of the tumblers are off-center, it will at once be apparent that either of the tumblers can be reversed endwise, relative to either other 70 tumbler or set of tumblers, so that the key engaging edge 42 of the tumbler 6, (Fig. 1) for example, is positioned adjacent the forward instead of the inner or rear face of the tumbler as clearly shown in dotted lines. 75 Furthermore, since the successive order of the tumblers shown can be variously changed, and since varying the vertical positions of the keyways 40, but a very small fraction of an inch will increase the key-changes, it 80 will be seen that the possible variations with such tumblers are practically infinite. At the same time the lock possesses the requisite so essential, namely, security, derived from 85 solidity and strength to resist violence and security against illicit opening. The key changes can be still further increased by cutting the groove 27 in the opposite side of the key.

The plug member 1 and tumbler mechanism carried thereby is inserted into the casing or barrel 2, from the face of the door, suitable inaccessible means being provided to prevent removal thereof. Upon inserting the plug member 1 into place the tumblers 90 6, 7, 8 and 9 carried thereby are restrained by the proper key 20 so that their upper and lower edges respectively lie within the periphery of the plug 1. When the plug 1 is arranged in place in the bore 3 of the barrel 2, the head 30 of the plug is arranged 101 for rotation in the co-axial pocket 10.

To prevent complete displacement of the tumblers from the plug 1 upon removing the plug from the barrel 2, grooves 60 are provided in one edge of each of the tumblers 6, 7, 8 and 9. These grooves, which are all of substantially the same height, are provided at various vertical positions in the respective tumblers. For example the groove 106 60 in the tumbler 9 is in close proximity to the upper edge thereof, while the groove 60 in the tumbler 8 is in close proximity to the lower edge of the tumbler. At the same time the upper portion of the groove provided in the tumbler 9 registers with the lower portion of the groove provided in the tumbler 8. A flat spring 61, shown in Fig. 7, is arranged longitudinally through the registering portions of these grooves 60. 110 This spring serves as a key to prevent the tumblers from being projected from the plug 1 to such extent as to allow complete displacement of the tumblers. 115

In the event that either of the coil springs 120 45 should break the spring 61 assures proper operation of the lock. In fact, the spring 45 might be readily dispensed with, in

which event the spring 61, due to its tendency to bring the grooves 60 into complete registration, would serve to project the tumblers into coöperation with the grooves 4 5 and 5 of the barrel 2, barring the plug 1 against rotation until the proper key has been inserted. The spring 61 is inserted from the rear through an opening 62 provided through the rear wall of the plug 1 10 and the guide blocks 22, 23 and 24 are preferably grooved to provide for the reception of the free forward end of this spring 61, as shown in Fig. 4.

While I have shown the grooves 60 as provided in only one edge of each of the tumblers, I contemplate the provision of such grooves in each of the opposite vertical edges of the tumblers whereby the opposite faces of the tumblers can be reversed without changing the relative positions of the upper and lower edges respectively of the tumblers. Semi-circular helical spring inclosing grooves, such as those provided in the opposite faces of each of the tumblers 20 adjacent one side of the slots or keyways 40, can be provided adjacent each side of these slots or keyways or these grooves and the spring 45 can be omitted entirely.

In the embodiment of my invention shown 30 in Figs. 8, 9, 10 and 11 the rotatable element of the lock comprises a U shaped bar 70, the free ends of the forwardly extending legs 71 of which are sprung into a head 72. Integral lugs 73 project transversely from 35 the ends of each of the forwardly extending legs 71 and engage in suitable diametrical slots 74, provided in the head 72, when the U shaped bar is sprung into place. The upper and lower edges of the front guide block 22' are milled down and the inner edge of the head 72 is swaged into these milled down portions to securely rivet the head in place. The rear end of the U shaped bar 70 is provided with a threaded opening 40 45 75 for the reception of a suitable bolt-throwing pin, not shown.

Keyway guide blocks 76 and 77 are arranged in spaced relation transversely between the legs 71 of the U bar 70. The opposite edges of these guide blocks are provided with projecting lugs 78 which projecting lugs are sprung into suitable openings provided in the legs 71 of the U bar 70. The tumblers 6', 7', 8' and 9' are arranged 50 55 transversely between the legs 71 of the U bar 70 and longitudinally between the guide blocks 76 and 77.

This type of construction allows for the accommodation of any desired number of tumblers, the spaced relation of the guide blocks 76 and 77 being varied accordingly to the number of tumblers required in the particular instance in point.

In this instance I have shown the tumblers 6', 7', 8' and 9' as center block tum-

blers, that is, the upper and lower edges of the slots or keyways 40' provided in these tumblers are inclined as shown at 41' from the opposite faces respectively of the tumblers to the key-engaging edges 42' which are thereby positioned substantially intermediate the opposite faces of the tumblers. In this particular instance the tumblers 6' and 9' are alike, as are tumblers 7' and 8', being simply reversed, end for end. Either 75 of these tumblers can be reversed endwise relative to either other tumbler or set of tumblers and the successive order of the tumblers shown can be varied to secure various key changes or combinations. Furthermore the relative vertical positions of the keyways 40' can be varied for the purpose of increasing the number of key changes. The key 20' shown is of a four step downward order, although of course 85 the particular number of steps is immaterial. It is to be noted that it is only necessary to offset the upper steps one half the thickness of the tumblers with respect to the lower steps. If the key-engaging edges 90 were flat it would be obviously necessary to offset these steps substantially the entire thickness of a tumbler.

Obviously the center block tumblers shown in Fig. 8 can be employed in connection 95 with the rotatable element shown in Fig. 1. Or the offset tumblers shown in Fig. 1 can be employed in connection with the rotatable element shown in Fig. 8. Further, the offset tumblers and center tumblers can be 100 combined in the same lock if so desired.

I do not intend to limit the invention to the particular details described, as I am aware that modifications and changes may be made and I have drawn the appended 105 claims accordingly.

I claim:

1. In a lock, a stationary element, a rotatable element, a pair of diametrically opposite grooves in said stationary element, a plurality of tumblers carried by said rotatable element, means normally projecting said tumblers into coöperation with said grooves to bar said rotatable element against rotation, and means for limiting the projection of said tumblers, said means comprising a spring arranged longitudinally through said tumblers.

2. In a lock, a stationary element, a rotatable element, a pair of diametrically opposite grooves in said stationary element, a plurality of tumblers carried by said rotatable element, said tumblers having coöperating pockets in their opposite faces, spring means confined in said coöperating pockets, said spring means normally projecting said tumblers into coöperation with said diametrically opposite grooves whereby said rotatable element is barred against rotation, and means for limiting the projec- 130

tion of said tumblers, said means comprising a spring arranged longitudinally through said tumblers.

3. In a lock, a stationary element, a rotatable element, a pair of diametrically opposite grooves in said stationary element, a plurality of tumblers carried by said rotatable element, spring means normally projecting said tumblers into said grooves to 10 bar said rotatable element against rotation, and spring means independent of said first spring means for limiting the projection of said tumblers.

4. In a lock, a rotatable element comprising a U-shaped plug member, a plurality of tumblers mounted between the limbs thereof, a head member carried by the free ends of said limbs, a keyway guide block in said head member, and a second 20 keyway guide block adjacent the rear end of said U-shaped plug member.

5. In a lock, a block tumbler having a keyway therein, said keyway having a key-engaging edge positioned off center relative 25 to the depth of the tumbler, the combination of the lock being changed by reversing the position of said off center key-engaging edge.

6. In a lock, a rotatable element, a plurality of tumblers carried by said rotatable 30 element, said tumblers having grooves in their longitudinal edges, spring means co-operating with said grooves to normally project said tumblers from the periphery of said rotatable element, the projection of 35 said tumblers being limited by said spring means.

7. In a lock, a rotatable element, a plurality of tumblers carried by said rotatable element, said tumblers having keyways 40 therein, said keyways having inclined key-engaging edges, said tumblers having co-operating pockets in their opposite faces and grooves in their longitudinal edges, spring means confined in said co-operating 45 pockets, said spring means normally projecting said tumblers from said rotatable elements, spring means co-operating with said grooves to limit the projection of said tumblers, said second spring means normally aiding said first spring means in the 50 projection of said tumblers.

8. In a lock, a rotatable element, a plurality of tumblers carried by said rotatable element, said tumblers having keyways 55 with inclined key-engaging edges and grooves in their longitudinal edges, spring means co-operating with said grooves to normally project said tumblers from said rotatable elements, said spring means limiting 60 the projection of said tumblers and a key for engaging the inclined key-engaging edges of said keyways to restrain the tumblers from projection from the periphery of the rotatable element.

65 9. In a lock, a stationary element, a rota-

table element, a plurality of tumblers carried by said rotatable element and adapted for co-operation with said stationary element, keyways in said tumblers, the vertical opposite edges of said keyways being inclined to the axis of rotation of the rotatable element, a key for engaging said inclined key-engaging edges to restrain the tumblers against projection from the rotatable element, the co-operating inclined shoulders 70 along the upper edge of said key being offset substantially one half the thickness of a tumbler with respect to the inclined co-operating shoulders provided along the lower edge of the key.

10. In a lock, a tumbler having a key engaging edge position off center relative the depth of the tumbler.

11. In a lock, a pair of adjacent tumblers, said tumblers having supplemental spring 85 sockets therein, a spring disposed in said supplemental spring sockets, one end of said spring engaging one of said tumblers, the opposite end of said spring engaging the other of said tumblers.

12. In a lock, a stationary element, a rotatable element, a pair of tumblers carried by said rotatable element, spring means confined between said tumblers, said spring means normally effecting engagement between said tumblers and said stationary element to lock said rotatable element against rotation, keyways or slots in said tumblers, said keyways or slots having key engaging edges and a key for co-operation with said 90 key engaging edges to disengage said tumblers from said stationary element whereupon said rotatable element is free to rotate.

13. In a lock, a stationary element having a bore, a groove adjacent said bore and an 105 enlarged coaxial pocket providing a shoulder at the termination of said bore, a rotatable element insertible in said bore, said rotatable element having a shoulder for co-operation with said first shoulder to limit the axial movement of said rotatable element through said bore and a plurality of tumblers, means for effecting engagement between said tumblers and said groove to lock said rotatable element against rotation 110 and means for effecting disengagement between said tumblers and said groove, whereupon said rotatable element is free to rotate.

14. In a lock, a stationary element, a rotatable element, a plurality of tumblers carried by said rotatable element, independent spring means between adjacent pairs of said tumblers for effecting co-operation between said tumblers and said stationary element, said tumblers having keyways or slots therein, and a key for co-operation with said keyways or slots to disengage said tumblers from said stationary element against the tension of said spring means.

15. In a lock, a stationary element, a rota-

table element and a plurality of tumblers, means normally projecting said tumblers to bar said rotatable element against rotation and spring means for limiting the projection of said tumblers.

16. In a lock, a stationary element, a rotatable element and a plurality of tumblers, spring means normally projecting said tum-

blers to bar said rotatable element against rotation and spring means independent of 10 said first spring means for limiting the projection of said tumblers.

In witness whereof, I hereunto subscribe my name this 20th day of August, A. D. 1919.

EDWARD A. CHRISTOPH.
